UNITED STATES PATENT OFFICE.

NICHOLAS M. DOTY, OF ALCESTER, SOUTH DAKOTA.

AUTOMATIC HOG OILER AND DISINFECTANT.

1,305,965.

Specification of Letters Patent. Patented June 3, 1919.

Application filed October 11, 1917. Serial No. 195,956.

To all whom it may concern:

Be it known that I, NICHOLAS M. DOTY, a citizen of the United States, residing at Alcester, in the county of Union and State of South Dakota, have invented certain new and useful Improvements in Automatic Hog Oilers and Disinfectants, of which the following is a specification.

This invention relates to an automatic oiling and disinfecting machine for hogs.

The primary object of this invention is to provide a device of this character which is simple and economical in construction and highly efficient in operation.

With the foregoing and other objects in view that will appear as the nature of the invention is better understood the same consists in the novel features of construction, combination and arrangement of parts illustrated in the drawings and more particularly pointed out in the appended claim. In the accompanying drawings:—

Figure 1 is a front elevation, partly in section, of an oiling and disinfecting machine for hogs, and embodying my improvements.

Fig. 2 is a vertical transverse section taken on line 2—2 of Fig. 1 with the parts shown on an enlarged scale, and Fig. 3 is a central longitudinal section of the oil discharging valve and associated parts.

Referring to the drawings for a more particular description of the invention and which drawings are for illustrative purposes only and are therefore not drawn to scale, the device comprises the oiling or disinfecting cylinder 1, consisting of the disk shaped end walls or members 2 connected together by the cross bars 3 and the flexible body 4 of cloth or other absorbent material.

The cylinder 1 above mentioned is revolvably mounted on the lower horizontal discharge pipes 5, connected at their outer ends to the lower ends of the vertical depending leg portions 6 of the feed pipes 7, the upper horizontal portions, as 8, of which, are connected through the medium of the coupling 9 and pipe 10 with the bottom of the supply tank or reservoir 11 for the oil or disinfectant. The depending leg portions 6 of the feed or conducting pipes 7 are slidably mounted in the longitudinal grooves 12 formed in the inner faces of the vertical members 13 of the upright frame A, the up-

per ends of which are connected together by the top cross bar 14.

The cylinder 1 is yieldably and adjustably supported in position in the frame A by the coil springs 15 connected at their lower ends to the upper horizontal members 8 of the feed pipes 7 and at their upper ends to the chains 16 engaged with the supporting hooks 17 secured to and depending from the top cross bar 14 of said frame. The chains 16 are for the purpose of adjusting the position of the oiling cylinder with relation to the height of the hogs.

The inner ends of the discharge pipes 5 are connected together by the cylindrical coupling sleeve 18 provided at one end with a depending discharge nozzle 19 normally closed by the valve 20 preferably formed at one end of the bar 21 and pivoted near said end as at 22, between the lugs or brackets 23, depending from and preferably cast integral with the oil cylinder 18. The opposite or free end of the bar 21 extended beyond the adjacent end of the coupling sleeve 18 and is guided in the vertical movement by the guides 23 depending from the latter.

The valve 20 is normally held closed by the spring 24 secured at one end, as at 25, to the bottom of the oil cylinder 18 with its opposite or free end bearing against the bar 21.

The free end of the bar 21 is equipped with a roller 26, which works against the edge of a double cam 27 carried by and rotatable with the cylinder 1, said cam being formed at opposite sides with the inwardly curved or depressed portions 28, the purpose of which will presently appear. A needle valve 29 screws into the coupling sleeve 18 and may be adjusted to regulate the amount of oil or disinfectant liberated each time the valve 20 is depressed.

In practice, as the hog passes under the cylinder 1, the latter is rotated which in turn rotates the cam 27 whereby the valve 20 is opened twice for each revolution of the cylinder by the action of the inwardly curved or depressed portions 28 of the cam 27 on the roller 26, against the action of the spring 24, the tendency of which is to keep the valve closed.

The oil or disinfectant which discharges through the nozzle 19 of the coupling sleeve 18, soaks through or saturates the cloth body

portion of the cylinder 1 which swabs or applies the same to the back of the hog over practically its entire length.

The machine is placed in a gate or doorway properly disposed in relation to the ground or floor in order that the hogs can readily pass under the rotating cylinder.

A plate 30 is arranged between the depending leg portions of the feed or conducting pipes 7 which prevents the hogs from jumping over the cylinder 1 and upon which may be displayed suitable advertising matter.

From the foregoing description taken in connection with the drawings, it is thought that the construction, operation, and advantages of this invention will be readily understood without requiring a more extended explanation.

Various changes in the form, proportions and minor details of construction may be resorted to without departing from the principles or sacrificing any of the advantages of this invention as defined in the appended claim.

Having described my invention, what I

claim as new and desire to secure by Letters Patent, is:—

A machine of the character specified comprising a rotatable oiling or disinfecting cylinder having a body of cloth or other absorbent material, a supply tank for the oil or disinfectant arranged above said cylinder and a stationary valve arranged within the cylinder and controlling the discharge of the oil or disinfectant, the operation of said valve being dependent on the rotation of the oiling or disinfecting cylinder and means for adjustably and resiliently supporting the oiling or disinfecting cylinder and associated parts and a cam carried by and rotatable with the oiling or disinfecting cylinder for opening the valve at pre-determined intervals during the rotation of the latter and a spring for closing the valve.

In testimony whereof I affix my signature in the presence of two witnesses.

NICK M. DOTY.

Witnesses:

A. O. OFSTAD,
LOWELL L. ENO.
